SLIDE-ON WELT DRAPERY HANGER

Michael Hardwick, Independence, Mo.

Application January 2, 1951, Serial No. 204,047

10 Claims. (Cl. 160—344)

1

This invention relates to drapery and traverse assemblies, and particularly to means for shiftably supporting window draperies so that the same may be removed for cleaning or replaced and properly held to present a neat appearance when the parts of the support and draperies are in the operative position.

One of the important aims of this invention is to provide a traverse assembly for draperies having parts for engaging specially designed elements forming a part of the draperies, and that will hold the draperies in a proper position to present a neat and desirable appearance not only to the gathered head of the draperies, but to the depending portion thereof which drops from the point of juncture between the traverse and drapery head.

A yet further aim of this invention is to provide a traverse and drapery assembly of the aforementioned character, wherein the means for coupling together the drapery and traverse parts is novel and unique in that conventional hooks, rings and other metal fasteners are eliminated and a part capable of being stitched to the drapery as the pleat of the head thereof is being formed is utilized to engage a cooperating complementary element of the traverse.

This invention has for a yet further object to provide a traverse assembly and drapery structure, which not only saves time and expense in producing and installing, but avoids the objectionable characteristics of previously employed hangers in that the drapery cannot accidentally jump from position as it is held with the center of gravity thereof directly beneath the main body of the traverse assembly to avoid binding and permit free sliding movement of the carriers.

Further objects of the invention include the provision in a traverse assembly of specially formed hangers mounted for free swinging movement; unique means for securing the cords of the traverse assembly to at least one of the drapery carriers; specially designed heads for engaging the cords of the traverse; end mounting brackets for removably engaging the heads to support the traverse assembly; intermediate supports for the tubular portions of the traverse which house the operating cords; and longitudinally slotted supports having a way for each stretch of the traverse cord.

Other objects of the invention including the specific manner of anchoring the cord to the master carrier; the special form of the hanger socket; and the character of welt used on the

2

drapery will appear during the course of the following specification, referring to the accompanying drawing, wherein:

Fig. 1 is an elevational view of the drapery and bracket assembly made in accordance with one form of the present invention.

Fig. 2 is a perspective view of one of the drapery units including a slotted hanger and its associated welt-fin element.

Fig. 3 is a cross-sectional view taken on line III—III of Fig. 1 but with the drapery in place.

Fig. 4 is a view similar to Fig. 3 showing another manner of using the hangers.

Fig. 5 is a detailed cross-sectional view taken on line V—V of Fig. 1.

Fig. 6 is an elevational view of the drapery and traverse rod assembly made in accordance with another form of the present invention.

Fig. 7 is an enlarged, fragmentary, detailed, vertical, cross-sectional view taken on line VII—VII of Fig. 6, but with the drapery in place.

Fig. 8 is a similar fragmentary, detailed, sectional view taken on line VIII—VIII of Fig. 6; and

Fig. 9 is a fragmentary, top edge view of the drapery heading illustrating the manner of securing the attaching welt in place.

It is contemplated by this invention to provide a strip of cloth welt, sewed into the back of a drapery pleat, to serve as means for anchoring a slide-on hook or hanger on the drapery for support in connection with any drapery rod having movable or stationary rings or slides with eyelets to receive the hook.

In the form of my present invention illustrated by Figs. 1 to 5, inclusive, there is included a support 10 for each of a pair of draperies, one only of which is illustrated in Fig. 1 and designated by the numeral 12. Draperies 12 (Figs. 1, 3, 4 and 5) are designed to be associated with a conventional window, the casement 14 (Fig. 1) whereof receives the support 10, normally for swinging movement on a vertical axis.

Support 10 comprises an elongated bar pivotally mounted upon the casement 14 as at 18 (Fig. 1) and having a plurality of tubular carriers 18 slidably mounted thereon and provided with a perforated ear 20, depending therefrom.

Each carrier 18 pivotally receives a depending hanger broadly designated by the numeral 22 through the medium of a hook 24 (Figs. 2-4) intermediate the ends of the elongated hanger 22 and passing through the perforation of ear 20. The hangers 22 each comprise an initially

flat, elongated bar that is longitudinally slotted as at 26 and provided with an eye 28 at the normally uppermost end thereof registering with the slot 26. It is noted that the eye 28 is angularly displaced with respect to the main body portion of the hanger 22 (see Fig. 4).

The draperies 12 have pleated headings 30 stitched as at 32 (Fig. 5) and equipped with a bead or welt 34. This welt 34 makes a longitudinal fin 36 extending between the pleated portions of heading 30 to be engaged by stitches 32. Welt 34 may be obtained on the open market and is commonly known as "slip-cover welting." The soft cotton cord is covered by fabric, and the marginal edges of this fabric strip which covers the cord produces fin 36, all to the end that the bead or welt 34 is flexible longitudinally to assume the position shown in Fig. 3. When bead 34 is moved into its hanger 22, fin 36 will be positioned in slot 26 and the bead 34 will be angled forwardly or outwardly until the lowermost edge of the fin 36 engages offset stop 38 at the lowermost end of the slot 26 (Figs. 2 and 3).

The center of gravity or major portion of the weight of draperies 12 will lie beneath the hangers 22 and thereby present a desirable appearance and allow easy manipulation of the drapery as the carriers 18 are adjusted on the support 10. The hangers 22 will hold the beads 34 in a rigid position where the arm 10 and all of the carriers 18 thereon, as well as the hangers 22, will be hidden from view behind draperies 12.

In the event that the drapery 12 does not hang properly, it is but necessary to cut through the bead 34 and through the fabric material covering the same as at 40 (see Fig. 4) to receive stop 38, thereby permitting positioning of the hanger 22 at a higher point on the bead 34 and with respect to the heading 30. The lowermost portion of the bead 34 below the cut 40 will accordingly be positioned below the stop 38, as is clear in Fig. 4 of the drawing.

The cut 40 should be positioned to assure that the upper end 28 of the hanger 22 will be behind and, therefore, concealed by the drapery 12. While the hangers 22 have been illustrated in Figs. 1 to 5, inclusive, as constituting a length of bar stock, it is obvious that the same might well be formed in other ways such as through use of a single length of wire or the like. In any event, the unit shown by Fig. 2 may be sold in quantities for use by householders generally in hanging draperies as desired.

In Figs. 6 to 8, inclusive, a support 110 extends substantially the full width of the area to be covered by the draperies 112 (Figs. 6 and 9) when the latter are in the closed position. In this illustrated embodiment, draperies 112 are designed to be associated with a conventional window, the casement 114 whereof receives the support 110 in a manner to be hereinafter set down.

As seen in Fig. 7, support 110 is preferably formed of sheet material to present a pair of ways or tubes 116 in communication with slots 118, formed through the substantially flat front wall of support 110, as illustrated in Figs. 6 and 7. It is preferable to form supports 110 in a manner to extend from edge-to-edge of casement 114 and to thereby avoid any weakness due to sliding sections, as is now sometimes the practice.

A number of freely-moving carriers 120 (Figs. 6 and 7) slidably engage slots 118 and should be moved to the operative position before a pair of opposed heads 122 are slipped into place at the ends of support 110 (one head 122 only being

shown in Fig. 6). A master carrier 124 (Figs. 6 and 8) likewise engages slots 118 but is wider than carriers 120 for the purpose of providing means for engaging the operating cord 126 shown in Fig. 8.

Master carrier 124 has anchoring tube 128 secured thereto through the employment of ears 130 or any other suitable mechanical means, and when tube 128 is so mounted upon carrier 124, pin 132 is moved to position as illustrated in Fig. 8. This pin penetrates cord 126 and passes completely through tube 128 and the front plate of carrier 124. After pin 132 has been so positioned, a tongue or detent 134 is forced thereagainst to preclude accidental displacement. Thus, cord 126 is securely anchored to master carrier 124, which in the instance illustrated is attached to each stretch of cord 126.

There is a master carrier attached to the stretch of cord 126 passing through the upper way or tube 116 and a master carrier 124 secured as above described, to the stretch of cord 126 extending through the lower way 116. The threading of cord 126 around the pulleys in head 122 is well known in the art.

Each head 122 has pulleys not shown, and a neck 138, the latter being secured to support 110 through the medium of a screw 140 (Fig. 6). This neck 138 has curled marginal edges (not shown) to embrace that portion of the front wall of support 110 between slots 118.

Mounting bracket 142 (Fig. 7), angular in form, engages head 122 at each end of support 110, and it is this bracket 142 which is attached to casement 114 or the wall to which draperies 112 are to be hung, by the later described support 148.

This support 148 is slotted as at 149 to receive one leg of mounting bracket 142, as illustrated in Fig. 7. The combination between these two members 142 and 148 allows bracket 142 to be extended prior to tightening the screws 151 which pass through holes in support 148.

A key-hole slot formed in one leg of bracket 142 engages a pin or screw 146 (Fig. 6) on head 122 to permit the removal of support 110 after brackets 142 have been rigidly fastened in place by support 148.

The intermediate support 148 is specially designed to embrace support 110, as illustrated in Fig. 7. Ears 150 on intermediate support 148 partially embrace the rounded edges of support 110 and the inherent resiliency of the material from which the support 148 is made, allows this element and support 110 to be snapped together. Lateral displacement of support 110 is thereby prevented and ears 150 maintain support 110 in a straight condition and against sagging or outward or inward bending.

Carriers 120 and 124 include as a part thereof specially formed depending hangers 152 pivotally mounted as at 154 for free swinging movement and are longitudinally slotted as at 156. These hangers are arched downwardly and rearwardly and have a stop 158 (see Fig. 7) at the lower ends thereof. These hangers 152 may be a part of bracket 142 and hung upon heads 122 if the nature of drapery 112 so requires.

The draperies 112 (Figs. 6 and 9) are identical with those previously described and have pleated headings 160 stitched as at 162 and equipped with a bead or welt 164. This welt 164 has a longitudinal fin 166 extending between the pleated portions of heading 160 to be engaged by stitches 162. When bead 164 is moved into its hanger 152, fin 166 will be positioned in slot 156 and

the bead 164 will be bent rearwardly and downwardly until its lower end engages stop 158. The center of gravity or major portion of the weight of draperies 112 will lie beneath the traverse assembly and thereby present a most desirable appearance and allow easy manipulation without binding and free from drapery distortion. The rigidity of bead 164 is sufficient to hold heading 160 in an upstanding position where the traverse assembly is concealed therebehind when draperies 112 are closed.

The elimination of metallic parts on draperies 112, permits cleaning of the draperies without the necessity of removing the traverse engaging parts, such as has been the case heretofore. The bead 164 in cooperation with the pivotal points 154 of hangers 152, will allow "settling" of the draperies 112 to assume a neatly gathered condition to enhance the appearance of the entire drapery body.

When the drapery and traverse parts are in the operative position, manual manipulation of cord 126 is easy. Downward pull on one knobbed end of the cord (Fig. 6), will move master carriers 124 toward the ends of support 110 to open draperies 112. A downward pull on the other knobbed end of cord 126 will move master carriers 124 toward each other, and thus, the draperies 112 will be closed.

The freely movable carriers 120 between heads 122 and master carriers 124 will be spaced-apart in accordance with the amount of drapery material lying between the beads or welts 164. Hanger 152 that is mounted upon bracket 142 will hold a portion of the marginal edge of draperies 112 in place around head 122 and thereby establish a snug connection between the outer edges of draperies 112 and the wall or casement 114 upon which the entire assembly is secured.

The quick movement of cords 126 will not cause draperies 112 to jump from their position on the traverse mechanism. Drooping and sagging of the heading 160 cannot occur and cords 126 cannot tangle nor fray due to friction. They are separately housed within case 116 and entirely free from each other.

The length of support 110 may vary to suit conditions, and this support may form a part of a mechanical or hand-traverse whether it be of the side arm, crane or conventional type above described.

The removability of heads 122 allows the introduction of any number of freely movable carriers 120 by the user. Bracket 142 may be extended outwardly to one side of the window or casement 114 in order that the draperies may cover an area substantially greater than the area of the casement and window. Such disposition of the parts of the traverse may take place to the end that the draperies may be drawn completely clear of the glazed opening of the window and allow free, unobstructed view therethrough.

The welt-slide bracket principle hereof presents a saving in labor for many reasons. Application of the hanger to the hook is much simpler than in cases of hooks that must be secured to the drapery. It is much easier to slide the bracket in place than to pin the same thereon, as in the case of safety-pin types of hangers. No additional steps of applying the welts are needed, since the same may be sewed in place at the time of forming the pleats. Upon removal of the drapery for cleaning, no separate detachment of metallic clips or other fixtures need take place.

It is obvious that the two forms of slotted hangers may be alternated between the two assemblies as desired; and it is understood that traverse rod assemblies and draperies embodying this invention may be made to present physical characteristics different from those illustrated and described. It is, therefore, desired to be limited only by the spirit of the invention and scope of the appended claims.

Having thus described the invention, what is claimed as new and desired to be secured by Letters Patent is:

1. In a traverse assembly adapted to hang draperies; at least one hanger having an elongated, vertically disposed slotted portion thereon; and a bead on the draperies having at least a portion of the length thereof within the slot of said slotted portion.

2. In a traverse assembly adapted to hang draperies; at least one hanger having an elongated, vertically disposed slotted portion thereon; and a bead on the draperies having at least a portion of the length thereof within the slot of said slotted portion, the lowermost end of the slot of said portion being closed, said bead engaging said closed end.

3. In a traverse assembly adapted to hang draperies; a plurality of hangers each having a vertically disposed inverted, frusto-conical, slotted portion thereon; and beads on the draperies having at least a portion of their lengths within said slotted portions respectively.

4. In a traverse assembly adapted to hang draperies; a plurality of hangers each having a vertically disposed inverted, frusto-conical, slotted portion thereon; and beads on the draperies having at least a portion of their lengths within said slotted portions respectively, said slotted portions being curved rearwardly from the draperies at their lower portions.

5. In a traverse assembly adapted to hang draperies; a plurality of hangers each having a vertically disposed inverted, frusto-conical, slotted portion thereon; and beads on the draperies having at least a portion of their lengths within said slotted portions respectively, said slotted portions being pivotally connected to the remaining portions of the hangers respectively.

6. In a traverse assembly adapted to hang draperies; a plurality of hangers each having a vertically disposed inverted, frusto-conical, slotted portion thereon; and beads on the draperies having at least a portion of their lengths within said slotted portions respectively, said slotted portions being curved rearwardly from the draperies at their lower portions, said slotted portions being pivotally connected to the remaining portions of the hangers respectively.

7. In a traverse assembly adapted to hang draperies; a plurality of hangers each having a vertically disposed inverted, frusto-conical, slotted portion thereon; and beads on the draperies having at least a portion of their lengths within said slotted portions respectively, said slotted portions being curved rearwardly from the draperies at their lower portions, said slotted portions being pivotally connected to the remaining portions of the hangers respectively, said slotted portions each having a stop thereon to limit the movement of the beads into their respective hangers.

8. In a traverse assembly adapted to hang draperies; a plurality of hangers each having a vertically disposed inverted, frusto-conical, slotted portion thereon; and beads on the draperies hav-

ing at least a portion of their lengths within said slotted portions respectively, said slotted portions being curved rearwardly from the draperies at their lower portions, said beads on the draperies being flexible to conform to the curvature of the slotted portions of the hangers.

9. In a traverse assembly adapted to hang draperies; a plurality of hangers each having a vertically disposed inverted, frusto-conical, slotted portion thereon; and beads on the draperies having at least a portion of their lengths within the slotted portions respectively; one of the hangers having structure for engaging a cord comprising a cord embracing member on the said one hanger, a pin for extending through the cord and a detent for holding the pin in place.

10. In a traverse assembly adapted to hang

draperies; at least one hanger having an elongated, vertically disposed slotted portion thereon; a lateral stop on one end of said slotted portion; and a bead on the draperies having at least a portion of the length thereof within the slot of said slotted portion, said bead resting on said stop.

MICHAEL HARDWICK.
